METHOD OF AND MEANS FOR DETECTING MISFED SHEETS

Arthur Wormser, Offenbach, near Frankfort-on-the-Main, Germany

Application February 18, 1935, Serial No. 6,949
In Germany March 1, 1934

7 Claims. (Cl. 271—57)

This invention relates to a method of and means for detecting sheets, which become mispositioned while being conveyed to registering devices or the like, more specifically, the invention applies to sheet detecting means by which the side edge or edges of a misfed sheet shall be detected.

Heretofore, in sheet feeding apparatus, the detecting devices, with the exception of plural sheet detecting means, were always so arranged that any error in the feeding of a sheet was not detected until it had approached its registering position. Such arrangements are quite satisfactory in cases where only small variations in the position of fed sheets occur. If, however, for any cause a sheet deviates considerably from its normal path of feeding, and consequently reaches the registering means very much out of position then, even though the detecting device may cause the operation of a printing press or other machine to stop, a mispositioned sheet might nevertheless advance into the machine.

In order to avoid such incidents, various devices have been used in the past, which devices, however, were of very delicate and complicated construction and usually associated with the detecting means at the front registering position.

It happens frequently that excess sheets are accidentally removed with the top sheet from a stack and carried along with it to the registering means. Such excess sheets invariably become mispositioned and may reach the front end of the registering table before the guides present themselves to the oncoming sheet, or they may reach the registering position during that period when the detecting means is inoperative.

One of the primary objects of my invention therefore is to provide a method and means whereby sheets which become considerably mispositioned in their normal path of travel, may be readily and effectively detected before they reach their registering position.

A further object of my invention resides in the provision of means whereby mispositioned sheets will be held against further forward movement.

A still further object is to provide detecting means which will be ready for operation at all times.

To accomplish these and other objects, which will become apparent from the following description and appended claims, I have provided means illustrated in the accompanying drawing, in which:

Figure 1 is a diagrammatic view of the principle involved in my invention;

Figure 2 is a partial cross section of Figure 1, viewed from the registering end of the sheet supporting means; and showing some conventional means whereby mispositioned sheets may be held against further forward movement.

My invention is based on the fact that misfed sheets usually extend considerably beyond their normal path of travel, so that the misposition of a sheet can be detected by means offset from the lateral limits of its normal path, that is, either at a point beyond such path, or within its limits.

Referring now to Figures 1 and 2, I propose to associate with the registering table 1, one or more photoelectric cells or similar devices, whereby a mispositioned sheet shall be detected before its leading edge reaches the registering guides, 2, 3. The broken lines 4, 5 indicate the lateral limits of the normal path of a sheet. In the particular form illustrated, I provide points 6, 7 located beyond said normal path and arranged so that light beams 6', 7' respectively, will be impinged continually on said points so long as the sheet 8 follows its normal path. However, should the sheet 8 become mispositioned, as shown in full lines in Figure 1, then its corners, that is to say one of its leading corners and one of its trailing corners, as they pass the points 6 or 7, will intercept the respective light beam and by suitable control mechanism, preferably actuated by a photoelectric cell or the like, the sheets will be prevented from reaching the front guides 2, 3.

In Figure 2 I have indicated diagrammatically one conventional device whereby mispositioned sheets may be held against further forward movement.

In order to accomplish this I preferably provide a plunger 9 which carries at its lower end a brake shoe 10 of rubber or any other suitable material. Normally, said plunger, which may slide freely within the cylinder 11, is held in its inoperative position against an expansion spring 12, by means of a magnet 13. However, when a mispositioned sheet covers either one of the points 6, 7, the electric circuit in lines 14 and 15 will be broken, thereby releasing the plunger 9 so that the latter will move down on to the misfed sheet and hold it against further movement.

It is important, of course, that the detecting device is adapted to operate without interruption because otherwise a mispositioned sheet may pass the detecting points at a moment during which the device is inoperative.

While I have illustrated a preferred manner whereby the objects of my invention may be accomplished, it should be understood that any

conventional arrangements may be readily adapted for this purpose. Such detector mechanism could include one or more electric contact points, such as 6, 7 shown in Figure 1 provided in the registering table, and cooperating contacts could be arranged above such points. The circuit of the current passing through these contacts would only then be broken when part of a misfed sheet becomes positioned between said contacts.

Another arrangement may include such means as a photoelectric cell arranged so that a light beam would continually impinge onto such cell, but be interrupted by a mispositioned sheet. Such cell could be located on one side only of the path of the sheets, in which event a mirror, suitably positioned on the other side of said path, could project a light beam onto said cell. Furthermore, any convenient pneumatic or mechanical detector device could be utilized advantageously.

Instead of placing the detector device beyond the limits of the normal path, as illustrated in the drawing, such device could be located within the limits of the normal path of the sheets and so adapted that it will operate when a sheet fails to reach the detector means. Whatever the form of modification may be, the detector and associated mechanism shall be operative at all times. It will also be understood that while I have illustrated my invention in connection with sheet feeding mechanism adapted for feeding individual sheets in succession, it may be readily adapted for use in connection with feeding apparatus whereby superimposed sheets are fed to registering means.

I claim:

1. In sheet feeding mechanism, the combination of sheet registering means, and sheet detecting means offset from the normal lateral limit of the side edges of fed sheets.
2. In sheet feeding mechanism, the combination of sheet registering means, and sheet detecting means positioned in advance of said registering means and offset from the normal lateral limit of the side edges of fed sheets.

3. In sheet feeding mechanism, the combination of sheet registering means, and sheet detecting means positioned in advance of said registering means and offset from the normal lateral limit of the side edges of fed sheets.

4. The method of detecting mispositioned sheets during their travel to sheet handling mechanism, consisting in advancing sheets within a predetermined longitudinal path, and detecting the lateral edge of a sheet so mispositioned.

5. The method of detecting mispositioned sheets during their travel to sheet handling mechanism, consisting in advancing sheets within a predetermined longitudinal path, detecting the lateral edge of a sheet so mispositioned, and holding a mispositioned sheet against further movement.

6. The method of detecting mispositioned sheets during their travel to sheet handling mechanism, consisting in advancing sheets within a predetermined longitudinal path, continually applying detecting means adjacent the normal lateral limit of the side edges of fed sheets, and detecting the lateral edge of a mispositioned sheet.

7. The method of detecting mispositioned sheets during their travel to sheet handling mechanism, consisting in advancing sheets within a predetermined longitudinal path, continually applying detecting means adjacent the normal lateral limit of the side edges of fed sheets, detecting the lateral edge of a mispositioned sheet, and holding a mispositioned sheet against further movement.

ARTHUR WORMSER.
